BOX FOR BINGO ACCESSORIES

Anthony J. Ventimiglia, 24901 E. Jefferson, Apt. 202,
St. Clair Shores, Mich. 48080

Filed Feb. 20, 1973, Ser. No. 333,899

Term of patent 14 years

Int. Cl. D31—00

U.S. Cl. D87—1 R

FIG. 1 is a perspective view of a box for bingo accessories showing my new design;

FIG. 2 is a perspective view thereof in an opened condition;

FIG. 3 is a right end elevational view;

FIG. 4 is a front elevational view;

FIG. 5 is a top plan view;

FIG. 6 is a rear elevational view; and

FIG. 7 is a perspective view of a modified form of the box for bingo accessories.

I claim:

The ornamental design for a box for bingo accessories, as shown and described.
